The ornamental design for a shoe sole, as shown and described.

DESCRIPTION

FIG. 1 is a perspective view of a shoe sole according to my new design;

FIG. 2 is a bottom plan view thereof;

FIG. 3 is a left side view thereof;

FIG. 4 is a right side view thereof;

FIG. 5 is a front view thereof;

FIG. 6 is a rear view thereof;

FIG. 7 is a bottom plan view of an alternative embodiment of the shoe sole according to the present invention, the appearance of the shoe sole being identical to the first embodiment except for an indication of surface contrast;

FIG. 8 is a left side view of the alternative embodiment; and,

FIG. 9 is a right side view of the alternative embodiment.

The uppermost broken lines in FIGS. 1 through 9 define the boundary of the design. The broken lines within FIGS. 1, 3, 4, 5, 8 and 9 form no part of the claim.
